UNITED STATES PATENT OFFICE.

HENRY J. NOLTE, OF SCHENECTADY, NEW YORK, ASSIGNOR TO GENERAL ELECTRIC COMPANY, A CORPORATION OF NEW YORK.

ELECTRON-DISCHARGE DEVICE.

Application filed September 18, 1923. Serial No. 683,471.

My present invention, which is a continuation in part of my prior application, Serial No. 443,005, filed February 7, 1921, relates to electron discharge devices, and more particularly to devices of the type employing at least three electrodes, comprising a cathode, an anode and a grid member for controlling the passage of an electron stream between cathode and anode.

10 The object of my invention is to provide a simple and efficient construction for such devices which will be particularly adapted for controlling large amounts of power. In carrying my invention into effect I provide 15 an evacuated receptacle, which is composed in part of glass or vitreous material through which leading-in wires may be readily sealed, and in part of metal, the metal part of the receptacle being adapted to serve as 20 anode for the device.

The novel features which I believe to be characteristic of my invention are set forth with particularity in the appended claims, the invention itself, however, will best be 25 understood by reference to the following description taken in connection with the accompanying drawing in which Fig. 1 is a view partly in section of one of my improved devices; Fig. 2 is a view of the grid 30 and the structure whereby it is supported; Figs. 3 and 4 are detail views of portions of the grid structure, and Figs. 5, 6 and 7 are detail views of a supporting structure 35 for the grid which may be substituted for the form shown in Figs. 3 and 4, while Fig. 8 shows a detail of the grid end rings.

As indicated in the drawing, I provide an evacuated receptacle comprising a portion 1 of glass and a portion 2 of metal.

40 The glass portion is sealed to the metal portion by means of a thin metal ring 3 which is preferably of copper or an alloy having substantially the same coefficient of expansion as the glass of which the part 1 is composed. This ring 3 is soldered or welded to the portion 2 and forms a gas-tight seal 45 with the glass at the region 4 where it is surrounded by the glass wall of the portion 1. The cathode 5, which is preferably of tungsten, is supported within the receptacle 50 by means of supporting arms 6, 7 and 8, the arms 6 and 7 also serving as supply con-

ductors to the cathode. In view of the fact that a large heating current must be supplied to the cathode in order to obtain a 55 large electron emission and large output from the device, the leading-in conductors 9 and 10 are subdivided into a plurality of parallel wires of smaller diameter at the region 11 where they are sealed through the 60 wall of the reentrant tubular portion 12 of the glass member 1 in order that a gas tight seal may be made more readily than it can be made with a single large conductor. The parallel portions of these leading-in 65 wires are secured to the supporting arms 6 and 7 by means of binding wires 13, and are also spot welded to the supporting arms at the points 14, as indicated. The grid 15 which surrounds the cathode is in the form 70 of a cylindrical screen made up of two sets of wires 16, 17, which are wound spirally in opposite directions and interwoven. By means of this construction the principal expansion of the grid when heated will 75 occur in the direction of its diameter and the tendency of the grid to buckle and make contact with the filament or anode will be largely eliminated. The ends of these two sets of grid wires are secured to end rings 80 21 by means of binding wires wound around these rings. Supporting arms 20 are secured to these two rings and together with the rings form a rigid support for the grid. These supporting arms and the end rings 85 preferably are made of tungsten or similar metal from which the occluded gas may easily be removed so there is no tendency for the evolution of gas when the parts are heated during the normal operation of the 90 device.

I have indicated in Figs. 3, 4, and 8 of the drawing one convenient way of uniting the arms 20 with the rings 21. These rings are formed of a strip of metal 21 stamped 95 out, as indicated in Fig. 4, with ears 22 projecting from its edges. The strip of metal is bent into the form of a ring, these ears bent over and the arms 20 inserted through the holes 23 in the ears 22. The arm 20, 100 which passes through the holes 23 at the ends of the strip which come opposite each other, also serves to hold the two ends of the strip together. After the arms 20 are

inserted in these holes the ears may be 5 squeezed or bent in such a way as to firmly grip the arms 20 and thereby secure the parts together without the necessity of any welded or soldered joints. The grid structure described is supported in the desired position in the receptacle by means of a sleeve 24 which surrounds the reentrant tubular portion 12, and is securely fastened 10 thereto by means of clamping screw 25. Supporting arms 26 are secured to this sleeve 24 and the members 20, which are of considerably smaller diameter than the diameter of the arms 26 are fastened to the 15 arms 26 in the manner indicated at 27 in Fig. 2. For convenience in the construction of the device the end of the portion 2 of the receptacle may be left open until the parts have been sealed together and then 20 closed by means of a cap 28 which is soldered to the receptacle or welded thereto to form an air-tight joint.

In the modification shown in Figs. 5, 6 and 7, the rings for supporting the grid are 25 made from flat metal strips 29, which are provided with punched out portions 30, which are so formed that the arms 20 are embraced between these punched out portions and the main body of the strip, as indicated in Fig. 6. In this case also the arm 20, which passes through the openings formed by the punched out portions 30 at the ends of the strip serves to hold the two 30 ends of the strip together. The strip 29, which forms the lower grid supporting ring 35 is also provided with openings 31 and the upper ends of arms 26 are slotted to receive the grid supporting ring. The sides of the slots in the arms 26 are then pressed into 40 the openings 31 as indicated in Fig. 7, thus securing the ring to the supporting arms without the necessity of any welded or soldered joint.

In the operation of the device described 45 for the control of large energies, the anode 2 should be artificially cooled. This may be accomplished by placing it in a bath of water or other suitable cooling liquid and providing means to insure good circulation 50 of the cooling liquid. In view of the fact, therefore, that the anode 2 will normally operate at a low temperature, it is possible to make use of metal for its construction having a comparatively low melting point. 55 I have found that copper is very suitable for this purpose.

In the exhaustion of the device described, to remove all air as well as all the gases occluded in the metal parts, I prefer as a preliminary step to heat the anode 2 by means 60 of heat radiated from the cathode 5. It is possible to heat the anode to red heat in this way and thereby drive off a large portion of the occluded gases. After the exhaustion has been carried on in this way

until the evolution of gas is greatly decreased or substantially stopped, a source of potential is connected between cathode and anode so that the anode will be bombarded by electrons emitted from the cathode. At 70 this point in the exhaust the cooling medium is applied to the anode and the gas removed during this stage is therefore removed principally as a result of bombardment. Occluded gas is also removed from the grid 75 structure by bombarding the grid and its supporting parts by electrons given off from the cathode.

While I have indicated and described the preferred embodiments of my invention, it 80 will be understood that my invention is by no means limited to the particular structures shown as many modifications in the arrangement of parts and their relation to one another may be made without departing from 85 the scope of my invention as set forth in the appended claims.

What I claim as new and desire to secure by Letters Patent of the United States is:—

1. A support for an electrode comprising 90 a strip of metal bent into the form of a ring, and a plurality of supporting arms which are surrounded by portions of said metal strip and thereby secured to said ring, one of said arms being surrounded by portions 95 located at opposite ends of the strip and serving to hold together the two ends of the strip.

2. A support for an electrode comprising 100 a strip of metal which is provided with stamped out portions and bent to form a ring, a plurality of supporting arms secured to said strip by said stamped out portions 105 the ends of said strip being held together by one of said supporting arms.

3. A support for an electrode comprising 110 a strip of metal having portions which project away from the plane of the strip at opposite edges thereof and a plurality of supporting arms which are embraced by said projecting portions and thereby secured to said strip, said strip being bent into the form of a ring.

4. A support for an electrode comprising 115 a strip of metal having portions which project away from the plane of the strip and a plurality of supporting arms which are embraced by said projecting portions and thereby secured to said strip, said strip being bent into the form of a ring and being 120 held together by the coaction of one of said supporting arms and said projecting portions.

5. A support for an electrode comprising 125 a strip of metal having portions which project away from the plane of the strip and a plurality of supporting arms which are embraced by said projecting portions and thereby secured to said strip, said strip being bent into the form of a ring, one of said 130

arms being embraced by projecting portions located at opposite ends of said strip and serving to hold together the two ends of the strip.

5. 6. An electrode support comprising a cylindrical grid having a ring at one end thereof, supporting arms for said grid having

slots in their ends for receiving said ring and openings in said ring into which the sides of said slots are pressed thereby securing the ring to the supporting arms. 10

In witness whereof, I have hereunto set my hand this 17th day of September, 1923.

HENRY J. NOLTE.
